W. H. STEVENS.
TOOL HANDLE.
APPLICATION FILED DEC. 23, 1920.

1,418,683.

Patented June 6, 1922.

Inventor:
William Hutton Stevens,
By *Broderick & Deeney* Attorneys.

UNITED STATES PATENT OFFICE.

WILLIAM HATTON STEVENS, OF HOLLIDAYSBURG, PENNSYLVANIA.

TOOL HANDLE.

1,418,683.

Specification of Letters Patent. Patented June 6, 1922.

Application filed December 23, 1920. Serial No. 432,860.

To all whom it may concern:

Be it known that I, WILLIAM HATTON STEVENS, a citizen of the United States, residing at Hollidaysburg, in the county of 5 Blair and State of Pennsylvania, have invented certain new and useful Improvements in Tool Handles, of which the following is a specification.

This invention is designed to provide an 10 improved handle for shovels, forks, picks and other tools.

My improved handle is characterized in its preferred form by the combination with a tubular metal core and a woven wire 15 skeleton fixed thereto, of a molded body such as wood or paper pulp, which surrounds said core and has said skeleton interlocked therein. The handle produced thereby has the desiderata of strength, durability and low cost.

The invention is set out in the following description and the accompanying drawings in illustration thereof.

In the drawings, Fig. 1 is a broken side 25 elevation of a handle embodying the invention; Fig. 2 is a broken part sectional plan view of the same, and Fig. 3 is a sectional view taken on the line 3*-3* of Fig. 2.

The handle, in the form illustrated, comprises a tubular metal core 1, of substantially the length and shape of the handle, and the tubular woven wire skeleton 2 sur-

rounding the core, spacing blocks or spools 3 together with rivets 4 fixing the core and skeleton together in approximately concentric relation with the desired space between them. A body of plastic material 5, preferably of light and fibrous character, such as wood or paper pulp, is molded and permitted to set upon the core 1 so that the 40 skeleton 2 shall be embedded in such body, which is finished or formed in the desired fashion.

Having described my invention, I claim:—

1. A tool handle comprising a tubular metal core, a molded body encasing said core, and means spaced from said core for fixing said core and body together. 45
2. A tool handle shaft comprising a woven wire skeleton and a molded body in which said skeleton is embedded. 50
3. A tool handle comprising a metal core, a perforated skeleton fixed to said core, and a body molded on said core and skeleton. 55
4. A tool handle having a body formed of wood pulp, a metal core extending substantially the entire length of said body, and a skeleton embedded in said body and fixed to said core.

Signed at Philadelphia, county of Philadelphia and State of Pennsylvania, this 21st day of December, 1920. 60

WILLIAM HATTON STEVENS.
